UNITED STATES PATENT OFFICE

2,537,125

COMBINED FEED TRAY AND MOISTENING DEVICE FOR DUPLICATING MACHINES

Frank Ronald Ford, Birmingham, England

Application April 9, 1947, Serial No. 740,443
In Great Britain November 16, 1945Section 1, Public Law 690, August 8, 1946
Patent expires November 16, 1965

2 Claims. (Cl. 101—132.5)

1

This invention relates to duplicating machines of the general class in which a copy sheet and a master sheet bearing in reversed script the matter to be reproduced are passed in pressure contact between a cylinder to which the master sheet is clamped and a pressure roller, the copy sheet being moistened before being brought into contact with the master sheet.

The object of the present invention is to provide certain improvements in this class of machine, one part of the invention being applicable to machines of the type in which the copy sheets are sudden into the machine from a feed tray and moistened by being brought into contact with a suitable moistening device.

With such machines it is a known practice to make the feed tray slidably detachable from the machine, its lateral edges being provided with tongues or flanges adapted to rest in or on guides formed internally of the side frames of the machine. In my prior U. S. A. Patent No. 2,399,176, issued April 30, 1946, I have proposed retaining the feed tray in position by means of pins passed through registering holes in the tongues or flanges and in the guides.

One part of the present invention is concerned with means whereby the feed tray may be more quickly secured in position, and consists in providing at each side of the tray a spring-controlled detent which when the tray is pushed into position rides past and engages behind an inturned flange or equivalent abutment on the adjacent side frame of the machine.

A further feature of the present invention is to construct the feed tray and moistening appliance, including the tank for holding the moistening liquid, as a single unit, these parts being connected by a rigid plate which forms the top of the tray and carries the tank on its underside and the support for the moistening pad on its upper side.

Another part of the invention concerns an improved construction of the feed tray itself, and consists in arranging such tray as the top of a box having its front end open and serving as a container for copy sheets to be used in the machines.

The floor of this box may be suitably dimensioned to support foolscap sheets in a flat condition, and at a higher level there may be arranged one or more shelves on which quarto and/or other sizes of sheets may be supported.

Another part of the present invention is concerned with moistening devices for duplicating machines such as the one described in my prior

2

U. S. A. Patent No. 2,424,534, issued July 22, 1947, and wherein the moistening fluid is fed from a tank by means of wicks to an absorbent pad on a carrier plate which is detachably secured to the underside of a rigid plate mounted above the tank, the upper end of the feed wicks being engaged between this latter plate and the pad.

Hitherto it has been my practice to provide the rigid plate with captive screws having manually operable heads and whose lower ends engage tapped holes in the pad carrier plate.

This part of the present invention is directed to facilitating the reconnection of the pad carrier to its supporting plate after removal therefrom, and consists in replacing the screwthreaded securing means aforesaid by spring-loaded plungers carried either by the rigid plate or the pad carrier, and each provided with a manually-operable head at one end, the other end of the plunger being of T or L shape and cooperating with an elongated hole in the coating member.

The invention is illustrated in the accompanying drawings, wherein:

Figure 1 is a view in side elevation partly in section;

Figure 2 is a fragmentary perspective view;

Figure 3 is a plan view; and

Figures 4 and 5 are sectional views upon the line 4—4 of Figure 3.

In the construction illustrated the invention is shown applied to a machine such as that described in the prior specifications referred to, and having two side plates 10 connected in spaced relationship by bolts or ties 11. Between the side plates is mounted the cylinder 12 for carrying the master sheet, and below the cylinder 12 is the pressure roller 13 adapted to press the moistened copy sheet against the master sheet on the cylinder. The pressure roller 13 is pressed towards the periphery of the cylinder 12 by means of springs in the known way, the pressure of which springs can be adjusted. The cylinder is provided with a shaft 14 which is operable by a crank handle 15, or alternatively the operating handle may be applied to a lay shaft which is geared to the cylinder shaft.

Referring particularly to Figures 1 and 2, the tray 16, over which the copy sheets are fed, is formed by a horizontal plate secured to a box-like structure 17 having side plates 18 and a front plate 19. The plate 16 is slotted, as shown at 20, and secured to the underside of the forwardly-projecting portion of the plate 16 is a tank 21 which contains the moistening liquid. At each end this tank is provided with an upwardly-pro-

jecting tubular portion 22, which portions pass through slots 20, one of which can be seen in Figure 2. At their upper ends the tubular parts 22 are secured to a slotted plate 23 which forms the support for the holder 24 of the moistening pad 25. The moistening appliance shown is constructed in accordance with my prior U. S. A. application Serial No. 651,265, filed March 1, 1946, which matured into Patent No. 2,530,426, November 21, 1950, and it is therefore unnecessary to describe it in detail. The pad holder 24 consists of an angle-section plate to which is secured a strip 26 having elongated openings 27. These elongated openings are engaged by T heads 28 of pins 29 which operate in openings in the plate 23. Each of these pins 29 is provided with a head 30 having a lever handle 31, and each head is provided with a cavity containing a spring 32. The heads 30 are locked to the pins 29 by means of grub screws 33, and the arrangement is such that normally the pressure of the springs 32 causes the heads 28 to clamp the pad holder to the underside of the plate 23, but the pins 29 can be turned on their own centres by means of the levers 31 to bring the heads 28 into line with the elongated openings 27, thus allowing the moistening pad holder to be readily removed from the moistening appliance (see Figure 5).

The box-like structure formed by the plates 16, 18 and 19 is intended to be used for holding copy sheets, and a shelf 34 may be provided within this structure having an end plate 35, this shelf being intended to support quarto-size sheets. Below the shelf on the base of the structure foolscap-size sheets may be stored.

The top plate 16 is provided with an opening 36 to allow of access to a screw plug 37 forming a closure for the filler opening of the tank. At their top edges the plates 18 are provided with angle-section strips 45 which engage over the edges of the plate 16.

The unit comprising the tray 16, the box-like structure 17 and the moistening appliance is supported on its own feet 67, and at the opposite end it is supported by providing the side plates 10 of the machine with horizontal grooves in which slide the edges of the forward parts of the plate 16.

Each of the side plates 18 on its inner side carries a detent 38 pivoted at 39 and having a latch-shaped nose 40 adapted to engage over a horizontal pin 41, these pins being carried by the side plates 10 of the machine. Each of the detents 38 is acted upon by a tension spring 42, and each detent further is provided with a laterally-projecting knob 43 extending through an arcuate slot 44 in the side plate 18, so that the detents

can readily be released from the pins 41 for removing the unit.

I claim:

1. In a duplicator a combined feed tray and moistening device for copy sheets comprising a plate forming a feed tray, a receptacle secured to the underside of said plate for moistening liquid, said plate having openings, upwardly projecting tubular portions on said receptacle, said tubular portions projecting through said openings, a slotted plate secured to the upper ends of said tubular portions, said plate being disposed above said tray, the underside of said slotted plate forming a seating for an absorbent pad, an absorbent pad clamped against said seating, an angle section carrier plate for supporting said pad, one limb of said carrier plate engaging one edge of said slotted plate, and the other limb of said carrier plate engaging the underside of said absorbent pad, a metal strip secured in the angle of said carrier plate, said strip and said other limb having elongated openings, spring loaded plungers mounted to slide and turn in openings in said slotted plates, said plungers having T heads at their lower ends, lever heads on said plungers to permit them to be turned, and a wick in said tubular portions for feeding liquid from the receptacle to the moistening pad.

2. A moistening device for a duplicator comprising a slotted plate, the underside of said slotted plate forming a seating for an absorbent pad, an absorbent pad clamped against said seating, an angle section carrier plate for supporting said pad, and the other limb of said carrier plate engaging the underside of said absorbent pad, a metal strip secured in the angle of said carrier plate, said strip and said other limb having elongated openings, spring loaded plungers mounted to slide and turn in openings in said slotted plates, said plungers having T heads at their lower ends, and lever heads on said plungers to permit them to be turned.
